UNITED STATES PATENT OFFICE

ALVIN G. SHERMAN, OF GROSSE POINTE, MICHIGAN, ASSIGNOR TO THE DETROIT VAPOUR STOVE COMPANY, OF DETROIT, MICHIGAN, A CORPORATION OF MICHIGAN

SELF-ALIGNING THERMOSTATIC VALVE ASSEMBLY

Application filed July 2, 1926. Serial No. 120,042.

This invention relates to self-aligning thermostatic valve assembly, and has to do particularly with the provision of a simple, efficient and economical valve construction in combination with a thermostatic actuating unit for controlling the supply of fuel to an oven or similar structure.

It is the object of the present invention to provide a thermostatically operated valve structure for controlling the supply of fuel to the furnace and it contemplates the provision of a simple valve structure which is self-aligning and freely floating with reference to the valve housing whereby a perfect valve action and seat is had under all conditions of operation. A further object of the invention has to do with the provision of a valve stem which is connected to the valve by means of a ball and socket joint whereby such valve stem will be operable to lift and permit seating of the valve without in any way affecting its true alignment and which valve stem at the same time may have such a fit with the valve housing as to effectively prevent the escape of any gas and at the same time serve as a connecting means between the thermostat device and the valve proper.

In the drawing:

20 The figure is a vertical longitudinal sectional view, illustrating an embodiment of the self-aligning valve structure, together with the heat responsive device as preferably positioned relative to a standard stove oven.

25 Hitherto in the use of heat control devices for controlling the flow of fuel to oven burners it has been customary to design a valve casing adapted to carry the heat responsive elements and also adapted to guide various means for translating the motion or action of the heat responsive elements to the valve or temperature controlling member within the casing. Much difficulty has been encountered in attempting to provide a gas tight joint between the valve and valve seat, and also between the interior of the valve casing and the interior of the heat responsive device. Many attempts have been made to overcome this objection, and some of such attempts have embodied the idea of divid-

ing the valve stem into two sections; one section being integral with the valve and extending a short distance within the valve stem guide and adapted to abut against one member of the heat responsive device, and other attempts have been made to provide various kinds of packing pins and various designs for packing for the pins between the valve stem and the heat responsive device. While some of these attempts have been more or less successful as to the provision of the gas tight joints between the valve casing and the heat responsive device, yet all of such structures have had some difficulty in providing a tight fit between the valve and valve seat for the reason that it has been difficult to accurately and relatively align and machine the guide for the valve stem and the surface of the valve seat.

The present invention overcomes these difficulties of the known prior art by providing a valve which is in a sense a freely floating valve with a ball socket, and a valve stem which projects through a guide in the valve housing and contacts with the valve at such ball socket so as to actuate the valve without in any way confining its movement.

Referring to the drawing which discloses one embodiment of the invention, the thermostatically controlled valve is shown as being mounted in an integral valve housing 1, which preferably comprises an integral casting with a chamber 2 therein. The valve casing is provided with a semi-partition 3 which serves as a valve seat to separate the chamber 2 and the chamber 4. The front of the valve casing is adapted to receive a suitable closure member 5 which preferably carries a spring 6 adapted to resiliently tend to close a suitable valve 7 against the valve seat 3.

The valve 7 is provided with a recess or semi-spherical socket 8 adapted to receive the rounded end 9 of a valve stem 10. The valve stem 10 is guided by and snugly fits within a suitable guide 11 formed as an integral part of the valve casing 1. It will thus be obvious that by connecting the valve stem with the valve by means of a ball and socket joint at the valve itself, and preferably within the plane of the valve, that at such valve 7

100

becomes a floating valve which is free to seat upon the valve seat 3 without in any way being confined by the position or alignment of the valve stem 10.

5 This arrangement of the valve and the valve stem makes it possible to utilize a heat control device, such as is fully described in a co-pending application, Serial No. 110,085, filed May 19, 1926. This heat control device 10 may comprise a suitable expansive member 12 adapted to be supported on one end by the extension 11 of the valve housing and a suitable nonexpansive member 13 adapted to contact with one end of the valve stem 10. 15 The expansive member or tube 12 is designed to be reciprocated back and forth with respect to the valve housing by means of a suitable lever 14 pivoted to the valve housing. This lever 14 may be oscillated about its pivot or fulcrum by means of a suitable screw plunger 15, operated and controlled by means of a suitable indicator 16, which is adapted to be positioned on the outside of the oven. It will be obvious that movement of the indicator member 16 will cause the screw plunger to be advanced or retarded to, in turn, cause the expansive tube 12 to be advanced or retarded relative to the valve housing. The non-expansive member 13 will be moved by a 20 corresponding movement of the tube 12 to actuate the valve stem 10, which in turn will unseat the valve 7.

It will thus be obvious that this novel self-aligning valve assembly makes it possible to 25 reduce the production and cost of the valve housing and the various parts therefor to a minimum, for the reason that the surfacing of the valve seat 3 and the boring or drilling of the valve stem guide may be accomplished 30 in a relatively rough manner without the necessity of accurately gaging and aligning and accurately carrying out such boring and surfacing operations. In other words, the provision of the ball and socket joint between 35 the valve and valve stem, at the valve, will enable the valve to be accurately and positively seated regardless of the accuracy of the alignment of the valve stem. This also permits the providing of a relatively snug fit between the valve stem and the valve guide to 40 prevent the escape of gas from the valve casting to the tube 12.

What I claim is:

1. A self-aligning thermostatic valve assembly, comprising in combination a seat, and a unitary valve therefor, a heat responsive device for controlling the actuation of said valve, a valve stem of uniform cross section for connecting said heat responsive device with said valve, said valve stem having a snug fit within a guide positioned between the valve casing and the heat responsive device, and a ball and socket connection between said valve and valve stem, said socket being 45 of greater diameter than the ball.

2. A self-aligning thermostatic valve assembly, comprising in combination, a valve casing having a valve seat, a unitary valve, a valve stem of uniform cross section and a guide therefor having a gas tight fit with the 70 stem, and a heat responsive device carried by the casing for actuating said valve stem, said stem being mounted independently of said device and being held in operative contact with said valve by a ball and open hemi-spherical socket joint. 75

3. A self-aligning thermostatic valve assembly, comprising in combination, a valve casing having a valve seat, a unitary valve, a valve stem of uniform cross section and a 80 guide snugly fitting the stem to render one side of the casing gas tight, and a heat responsive device carried by the casing for actuating said valve stem, said stem operatively contacting with said valve by a ball and open 85 hemi-spherical socket joint positioned substantially in the plane of the valve.

4. A self-aligning thermostatic valve assembly, comprising in combination, a valve casing having a valve seat, a one piece valve 90 stem having a rounded end and a guide therefor, an integral disc valve having a substantially centrally located relatively large concave depression formed therein which operates with the rounded end of the valve 95 stem to permit of relative movement between said valve and valve stem, and a heat responsive device carried by the casing for actuating the said valve stem, said stem and guide having a snug fit and being the sole means for 100 sealing the valve casing from the heat responsive device.

In testimony whereof I have affixed my signature.

ALVIN G. SHERMAN.
